L. B. CASON,
HAIR STRAIGHTENING COMB.
APPLICATION FILED FEB. 17, 1921.

1,413,255.

Patented Apr. 18, 1922.

INVENTOR:
Louisa B. Cason,
BY John Stein Jones,

ATTORNEY.

UNITED STATES PATENT OFFICE.

LOUISA B. CASON, OF CINCINNATI, OHIO.

HAIR-Straightening Comb.

1,413,255.

Specification of Letters Patent. Patented Apr. 18, 1922.

Application filed February 17, 1921. Serial No. 445,773.

To all whom it may concern:

Be it known that I, LOUISA B. CASON, a citizen of the United States of America, and a resident of Cincinnati, in the county of 5 Hamilton and State of Ohio, have invented a certain new and useful Improvement in Hair-Straightening Combs, of which the following is a specification.

This invention relates to hair flattening 10 or straightening devices in which a bar or backing having a deeply serrated or toothed edge is used and adapted to be heated and to have the combed hair taken in suitable quantities or swaths along the head of a 15 person and drawn taut as it will stand the pull over the said bar or backing and thereby relieved of its natural or other tendency to undesirably kink or curl, and the prime object of the invention herein is to provide 20 a longitudinal bar or backing of forged steel or the like having along one edge an integral series of parallel deep teeth that are preferably slightly convexed on their outer edges and likewise concaved on their 25 inner edges, such bar having a rectangular cross-section and its inner end extended into a tang whereby it is secured in place in a wooden or other non-conductor handle for due manipulation in the kinky or curly hair 30 that is taken in swaths in engagement with and along said teeth for proper separation and spreading in contact with the said bar when heated and wrapped or wound around the latter so that it can be sufficiently drawn 35 without severing but enough to make it taut and flat or straight and the kinks removed, without injury to the scalp or to the hair, or discomfort to the person during the treatment.

40 In the accompanying sheet of drawings, Figure 1 is a perspective view of the device embodying my invention in its most approved form, and Figure 2 is a transverse section taken on the dotted-line 2, 2 of Figure 1.

45 3 indicates the main head-bar or body-portion of the device, of rectangular cross-section, and having along one side thereof a series of integral, parallel teeth 4 whose 50 outer faces 5 are somewhat curved or convexed starting from a point 5^a at the outer lower edge of the bar 3 and terminating at the tip 5^b, and whose inner faces 6 slightly curve inwardly from said tip to a point 6^a

and then take a more direct or decided curve 55 6^b till the inner, lower edge of said bar is reached, all as best shown in Figure 2, and which structure I find has been the most practicable for the purpose named herein. In Fig. 2 it will be very plainly seen that 60 the head-bar or body-portion 3 is of exactly square cross-section along the respective teeth pits, whereby four distinct or decided corners or rectangular edges are presented to the kinky hair that is to be wound around 65 the said head-bar several times, or at least one full turn to attain the desired degree of tension or friction thereon while the teeth are passing through said hair in the flattening and straightening operation hereinafter 70 described.

7 is a pointed tang formed integral with the inner end of the head-bar 3 and inserted in a handle 8 of wood or other suitable non-conducting material. The customary metal 75 ferrule 9 is placed on the tang 7 at the inner end of the handle.

The head-bar, together with the integral teeth and tang, are preferably made of hand-forged steel, and the heat is applied to said 80 head-bar and teeth at the desired temperature that will not burn or otherwise injure the hair or the scalp. Such material is lasting and will not be easily bent or broken in handling.

85 In the operation of the device the heated comb is set with its teeth in engagement with a swath of the kinky or curly hair and then turned on its longitudinal axis so that said hair shall be wrapped or wound around 90 the head-bar tight enough to permit a drawing or pulling on the kinky or curly hairs through the teeth but with sufficient tension on the four corners of the head-bar 3, along the lines of the respective teeth pits, to 95 stretch them straight along the said head-bar, the heat of the teeth somewhat drying the hair at the time and the heat of the head-bar along its flat back-surfaces and angles being also sufficient to make such stretching 100 lasting and resulting in the desired flattened condition of the hair, entirely free from kink or curl, and to readily lie flat, as well as to comb flat with the ordinary comb, as the user wishes. It is preferred and desirable 105 to use oil of a suitable nature and consistency on the hair before applying my device herein to make it pliable as well as

stretchable without easily severing or parting under the tensile strength required to draw it out for straightening.

I claim:—

- 5 A hair straightening or flattening comb comprising a longitudinal metal head-bar or body-portion having a securing-tang provided at one end thereof, a longitudinal series of integral parallel pointed teeth projecting from one outer corner-edge of the said head-bar and each tooth having a convex outer surface and a deeply concaved or inwardly-curved inner surface, said head-bar being of square cross-section with four
- 10
- 15 decidedly-square corner-edges along the line of the respective teeth pits and adapted to

form a backing or supporting-surface for the spread-out hairs when separated and wound thereover and in contact with the said square or rectangular corners for the required drawing thereon in the direct and resultant straightening or flattening operation while the comb is in a properly heated state, and a wooden or other suitable non-conductor handle in which the said tang is inserted for the proper holding and manipulation of the comb in heating same as well as in its use on the head of the person in the said treatment of curly or kinky hair, substantially as herein shown and described. 30

LOUISA B. CASON.
